(57) **CLAIM**

The ornamental design for a combination glove, electronic device holder, and keyboard, as shown and described.

DESCRIPTION

FIG. 1 is a top perspective view of a combination glove, electronic device holder, and keyboard, showing the new design, receiving an electronic device;

FIG. 2 is a top perspective view thereof, with electronic device removed;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof; and,

FIG. 9 is a cross sectional view taken along line 9-9 in FIG. 3.

The dashed broken lines illustrate environment. The remaining broken lines illustrate portions of the combination glove, device holder, and keyboard that form no part of the claimed design. None of the broken lines form part of the claimed design.

1 Claim, 7 Drawing Sheets
